INVENTOR

Emil Ney

United States Patent Office.

EMIL NEY, OF NEW YORK, N. Y.

Design No. 3,750, dated November 16, 1869.

DESIGN FOR A SIGN.

The Schedule referred to in these Letters Patent and making part of the same.

To all whom it may concern:

Be it known that I, EMIL NEY, of the city, county, and State of New York, have invented a new and original Design for Sign; and I do hereby declare that the following is a full, clear, and exact description thereof, which will enable others skilled in the art to make and use the same, reference being had to the accompanying drawing, forming part of this specification, in which is represented a perspective view of my new design for a sign.

This invention relates to a new design for a sign, which is intended to be used in front of a cigar or tobacco-store.

The design represents the figure A of a woman

seated upon a velocipede, B, with the lower extremities upon the crank *a* of the same.

One hand of the figure is placed upon the steering-handle *b* of the velocipede, while the other hand holds the cigar *c*.

Having thus described my invention,
I claim as new, and desire to secure by Letters Patent—

The design for a sign, as shown.

EMIL NEY.
